UNITED STATES PATENT OFFICE.

EPHRAIM R. MILLER AND BARTLETT A. BOWERS, OF FREDERICK, MARYLAND.

TONGUE-DEPRESSOR.

1,187,079.

Specification of Letters Patent. Patented June 13, 1916.

Application filed June 15, 1915. Serial No. 34,192.

To all whom it may concern:

Be it known that we, EPHRAIM R. MILLER and BARTLETT A. BOWERS, citizens of the United States, residing at Frederick, in the county of Frederick and State of Maryland, have invented certain new and useful Improvements in Tongue-Depressors; and we do hereby declare the following to be a full, clear, and exact description of the invention, such as will enable others skilled in the art to which it appertains to make and use the same.

The general object of this invention is to improve the construction of tongue depressors, so that no pressure will be exerted on the dorsum or top of the tongue of the patient, when the depressor is in operative position, thereby preventing gagging of the patient; also to provide a depressor that can accommodate various sizes of tongues, simple in construction, cheap to manufacture, and so constructed that it will admit of every part of the depressor being thoroughly cleaned to render the entire device sanitary; and to this end the invention consists in the provision of a pair of elongated bars, of unequal lengths, one end of each bar being provided with an enlarged U-shaped head adapted to engage the tongue of a person, one of the heads being larger than the other head, and each having its sides formed to agree with the shape of the tongue, the said elongated bars, when in operative position, adapted to lie at right angles to each other and having detachable connection with each other, and when in inoperative position, to overlie and to have connection with each other so as to occupy a minimum amount of space.

Other objects will appear and be better understood from that embodiment of our invention of which the following is a specification, reference being had to the accompanying drawings forming a part thereof, in which:—

Figure 1 is a perspective view of the depressing bars when in operative position, Fig. 2 is a detail perspective view of the connecting end of one of the bars, Fig. 3 is a detail perspective view of the connecting end of the other depressing bar, and Fig. 4 is a perspective view of the depressing bars when in inoperative position, showing the same in superposed position.

Referring to the drawings more in detail, the letter *a* designates the tongue depressor,

as an entirety, and which depressor includes a pair of elongated bars 1 and 2, each having one end provided with an elongated U-shaped head, the head carried by the bar 1 being designated by the numeral 3, and the head on the bar 2 being shown at 4. The sides of the U-shaped head, are spaced sufficiently from each other so that no pressure will be exerted on the dorsum, or top of the tongue of the patient, when the depressor is in depressing position, thereby preventing gagging of the patient. The bar 1 is of a length greater than the bar 2, and likewise the head 3 is of a greater size than the head 4, which is carried by the bar 2. By virtue of having the bars and heads of unequal sizes, various widths of tongues can be accommodated. Each U-shaped head has its sides, which are designated respectively, by the numerals 5 and 6, longitudinally curved and also transversely curved, so as to conform with the shape of the tongue. When in operative position, the bars 1 and 2 are adapted to lie at right angles to each other, as shown in Fig. 1, so that when the heads carried by one of the bars is inserted into the mouth, the opposite bar will lie vertically and form a hand grip whereby pressure may be exerted upon the bar which extends into the person's mouth, resulting in the depression of the person's tongue.

In order to hold the arms in the angular relation, the bar 1 is provided with an elongated lug 7, which extends longitudinally of the bar 1, as shown in Fig. 2, and has its sides beveled in the direction of the adjacent side of said bar 1, the said lug being located adjacent the end opposite the end having the tongue engaging head 3 thereon, and the bar 2 has the end opposite the end carrying the head 4, provided with a dove tailed opening 8 adapted to receive the lug 7, as shown in Fig. 1, and has its walls 9 arranged in diverging relation, to agree with the restricted width of the lug 7. The bar 2 is also provided with a longitudinal slot 10, one end of the slot opening into the end, in which the opening 8 is located, and communicates with the opening as shown in Fig. 3. The bars 1 and 2 when in inoperative position and placed in superposed relation, as shown in Fig. 3, the slot 10 in the bar 2 is adapted to receive the lug 7, so that said bars will have connection with each other. When the bars are arranged in su-

perposed position, said bars will occupy a minimum amount of space, so that the depressor can be carried in a medical case.

Having thus described our invention, 5 what we claim as new is:—

1. A tongue depressor comprising, a pair of depressing bars of unequal length, adapted when in operative position to lie at right angles to each other, the smaller bar having 10 one of its terminals provided with a transversely extending slot restricted toward one end, the longer bar having a longitudinally extending lug thereon located adjacent one of its terminals and decreasing in width 15 throughout its length, the said longitudinally extending lug on the longer bar being adapted to be received by the transverse slot in the smaller bar, so as to hold the said bars in the angular relation.
- 20 2. A tongue depressor comprising a pair of depressing bars, one of the bars having one terminal provided with a transversely extending slot decreasing in width toward one end, the said bar having a longitudi-

nal slot therein having one end opening into the transverse slot and restricted toward its opposite end, the other bar having a longitudinally extending lug thereon, adjacent one terminal and decreasing in width throughout its length, the said depressing bars when in operative position lying at right angles to each other and the longitudinally extending lug of the second mentioned bar received by the transverse slot in the first mentioned bar, and when in 30 inoperative position superposed on each other and to have the longitudinally extending lug on the second mentioned bar detachably received by the longitudinal slot in the first mentioned bar, as and for the 35 purpose specified.

In testimony whereof we affix our signatures in presence of two witnesses.
